EDWARD MILLER, OF HUNTINGTON PARK, CALIFORNIA, ASSIGNOR TO EVANS PRODUCTS COMPANY, OF DETROIT, MICHIGAN, A CORPORATION OF DELAWARE

RIVING MACHINE

Application filed June 24, 1929. Serial No. 373,158.

This invention relates to riving machines and has for its principal object the provision of a new and novel construction whereby an article of more uniform thickness and of 5 smoother surface may be obtained than with those constructions now conventionally employed.

Another object is to provide a riving machine in which strips of material are removed by a knife from a block of stock by 10 a true slicing operation.

Another object is to provide a riving machine in which both the block of stock and the knife edge are disposed at an angle to 15 the relative path of movement of the knife.

Another object is to provide a riving machine in which the stock is automatically compressed between the knife edge and the table during the cutting operation.

20 Another object is to provide a riving machine having a table angularly positioned with respect to the plane of movement of the cutting edge.

Another object is to provide a riving machine having an angularly adjustable table.

Another object is to provide a riving machine having a knife whose upper surface recedes downwardly away from the cutting edge, and which upper surface is provided 30 with a plurality of vertically adjustable bearing members or buttons at points spaced from the cutting edge.

A further object is to provide means preventing distortion of the trailing end of the 35 cutting edge of the knife of a riving machine by the pressure of the veneer strip being cut by the same.

The above being among the objects of the 40 present invention, same consists in certain novel features of construction and combinations of parts to be hereinafter described with reference to the accompanying drawings, and then claimed, having the above 45 and other objects in view.

In the accompanying drawings, which illustrate the suitable embodiment of the present invention, and in which like numerals refer 50 to like parts throughout the several different

Fig. 1 is more or less a diagrammatic plan view of a riving machine.

Fig. 2 is a sectional view taken on the line 2—2 of Fig. 1.

Fig. 3 is an enlarged sectional view taken 55 on the line 3—3 of Fig. 1.

Fig. 4 is an enlarged sectional view taken transversely through the knife of the riving machine.

It has long been attempted in riving machines to produce a construction by which a true slicing action of the stock will result. This is desirable because of the fact that by a 60 true slicing action a smoother cut may be obtained and less energy expended in making 65 the cut. As far as I am aware, the attempts to attain this slicing action have taken the form of positioning the cutting edge of the knife at an angle to the path of travel of the knife and placing the block of stock square 70 with respect to the path of travel of the cutting edge of the knife. In this respect these constructions have failed to obtain a true slicing action for it will be apparent that in such 75 constructions each increment of length of the cutting edge of the knife moves straight through the block of stock without the lateral movement necessary to obtain a true slicing action.

In other words, in such constructions the point on the cutting edge meeting a side 80 edge of the block continues through the block in the same relation to such side edge. Consequently, it is obvious that there can be no true 85 slicing action with such a construction. I have discovered that the angularity of the cutting edge of the knife to the path of travel has no relation to the obtaining of a true slicing 90 action of the knife on the stock, but that this true slicing action can only be obtained by properly angularly positioning the grain of the stock with respect to the path of movement of the cutting edge of the knife, and this fact has never been realized heretofore.

However, in order to realize certain other advantages, such as a minimum distance of 95 travel of the knife, which permits a lighter and faster cutting machine, I prefer not only to place the grain of the wood at a predetermined angle to the path of travel of the cutting edge, but also to position the cutting 100

edge itself at an angle to the path of travel of the knife. Furthermore, I prefer to place the cutting edge at an angle of 45° or less to the direction of its movement. The result is that when the knife passes through the stock each point on the cutting edge thereof travels in a relatively diagonal path through the block. In other words, each point on the cutting edge travels simultaneously towards two adjacent sides of the block of stock,—thus resulting in a true slicing action. Inasmuch as the grain in such stock always extends in parallel or substantially parallel relation to one of the sides of the block of stock, the entire extent of such block being engaged at once by some point in the blade and each point of the cutting edge moves simultaneously across and with the grain of the wood, this mode of engagement and relative advance, whether produced by manipulation of the knife or by manipulation of the block, or by a combination of the two, being herein-after referred to as a "whittling" type of cutting action.

Another difficulty in connection with conventional constructions of riving machines is that considerable difficulty has been experienced in obtaining a veneer-like strip of uniform thickness throughout by the cutting action of a riving machine. I have found that if sufficient pressure can be exerted to urge the block of stock towards the table, a strip of stock of uniform thickness will be removed from the block of stock. However, it is impractical to apply to the top of the block of stock sufficient pressure to obtain the desired result, for in such case the friction of the stock on the top surface of the knife causes an undue heating of the knife edge with consequent distortion thereof, which in itself causes a variation in the thickness of the strip removed. I have discovered a construction by which any desired amount of pressure may be exerted on the stock being cut between the knife and the table only, this means being automatic in operation and eliminating the necessity of applying more than a nominal amount of pressure to the top of the block of stock, thus eliminating any possibility of the friction between the upper surface of the knife and the block of stock endangering the true form of the cutting edge.

Referring to the drawings, I show a riving machine including a frame having a pair of side bars 10, each of which carries an angle iron member 11 extending longitudinally thereof which forms a track for the carriage 12 which is adapted, in case the work is held stationary, as shown, to slide back and forth between the frame side members 10. The carriage 12 is shown as provided with a knife-supporting portion 13 which may extend from one near end and corner of the frame 12 towards the opposite corner or end thereof. The angularity of this portion 13

with respect to the direction of the path of travel of the knife, controls the same angularity of the knife and is shown in the drawings as approximately $16\frac{1}{2}^\circ$, this being a preferable amount for a block of stock of the relative proportions shown. This supporting portion is shown as provided in its upper surface with a plurality of transverse inclined grooves 14, in each of which is received a wedge member 15 controlled in its 70 slidable position through an adjusting screw 16. The knife 17, which preferably extends parallel to the supporting portion 13, then seats upon the upper surfaces of the wedges 15 and its upper surface is slightly inclined 75 to the horizontal, as indicated in Fig. 3, with the cutting edge 18 thereof positioned at the highest point of the blade. The knife 18 is shown as clamped down against the wedges 15 and the wedges 15 may be clamped in the 80 grooves 14 by screws such as 19 which extend up through enlarged openings 20 in the portion 13 and through the elongated slots 21 in each of the wedges 15 and thread into the body of the knife 17. The blades 85 17 is shown as also provided with a plurality of button members 22 on its upper surface, positioned away from the cutting edge 18 for the purpose of preventing the block of stock, during operation of the machine, from tipping over on to the face of the knife after the knife has passed through more than half of the block of stock. All of this method of supporting the knife edge thus far described is the same as that explained 90 in detail in my application for Letters Patent of the United States for improvements in riving machine filed August 27, 1928, and serially numbered 302,209. The only difference in the construction thus far described 95 is that in the present instance the knife 17 is positioned at an angle to its path of travel and the button members 22 are vertically adjustable, this adjustment being taken care of as indicated in Fig. 4 by threading the 100 shank 23 of the button members through the knife 17. The reason for this vertical adjustment is to provide means whereby these button members may be adjusted to a pre-determined vertical relationship with respect 105 to the cutting edge of the knife when such cutting edge has been relatively lowered by a sharpening operation carried out as described in my above mentioned previously 110 filed patent application.

The table 30 in the present case is shown as provided with one edge which extends in parallel relationship with respect to the cutting edge of the knife, and immediately below the same. This edge is provided with 115 a pressure bar 31 which may be secured in place by set-screws such as 32 and adjusted vertically by means such as shims 33. The height of the pressure bar above the table is shown exaggerated in the drawings for 120

the purpose of ease of explanation. This feature is described in my previous application above referred to. The table in the present case, however, instead of being formed as an integral part of the frame 12, or being rigidly secured thereto, is shown mounted upon the frame 12 in the following manner: Each end of the table 30 is provided with a downwardly extending lug 34 adjacent to the pressure bar 31 and the frame 12 is provided with a pair of upstanding cooperating lugs 35. A pin 36 is provided between each of the lugs 34 and its corresponding lug 35 so that the table 30 as a whole may pivot about the common horizontally extending axis of the pins 36. The free edge of the table may be supported in the following manner: A plurality of vertically extending screws 37 are threaded through the frame 12 and are each provided at their upper end with a ball 38 which is received in corresponding but elongated recesses 39 formed in the under face of the table, and are maintained in such position by means of plates such as 40 secured by screws such as 41, or other suitable means, to the under face of the table 30. The recesses 39 are elongated to permit the ball ends 38 to slide laterally of the table during adjustment thereof. These ball ends may, if desired, be left off, and the ends of the screws 37 be permitted to merely bear against the lower face of the table. The lower end of the screws 37 may be provided with a head such as 42, upon the periphery of which may be formed a plurality of indicating marks such as 43 which are adapted to co-operate with a downwardly extending blade 44, secured by screws such as 45 to the frame 12 and provided with indicating markings such as 46, so that the relative vertical position of each of the screws 37 and, therefore, the angular position of the table 30 about the pins 36, may be definitely determined and adjusted. These markings may be calibrated to read in decimal parts of an inch if desired. The side members 10 may support a frame indicated generally as 50 upon which may be carried rigid hopper members 51, 52 and 53 and a spring pressed slidible hopper member 54, in conformance with the hopper construction disclosed in my previous patent application above referred to. The hopper is so positioned relative to the cutting edge 18 of the knife 17 that one of its sides is parallel to such cutting edge as indicated in the drawings; and it will be understood that, in case only the knife 17 is slidable, as described, this hopper may be rendered stationary by securing the ends of frame 50 to side members 10.

The block 55 of wood stock from which the veneer strips or plates are to be removed by the knife is assumed to have been cut to suitable dimensions and positioned in the hopper

with its grain preferably positioned in parallel relation with respect to the cutting edge 18 of the knife. Pressure, either manual or provided by a weight, may be applied to the top of the block 55 of stock so as to urge it downwardly in the hopper. The carriage 12 is reciprocated in any suitable manner. As the carriage approaches one end of its path of travel the block 55 of stock is cleared from over-lapping relationship with respect to the knife 17 and moves downwardly into contact with the table 30. As the knife returns on the next stroke, the blade engages that portion of the block disposed between its cutting edge and the pressure bar 31 and slices off such portion from the under side of the block of stock. It will be understood, of course, that during this slicing operation each point on the cutting edge 18 in cutting through the block 55 will move simultaneously toward the hopper members 51 and 52, against which rest corresponding sides of the block 55. In other words, each point of the cutting edge in passing through the block of stock moves simultaneously towards two adjacent sides of the block, simultaneously across and in the direction of the grain of the wood, and thus a true "whittling" type of slicing action of the wood by the knife is obtained. I have found that this true slicing action, which to my knowledge has never before been obtained in a riving machine, results in a veneer strip or plate being cut from the block which has an extremely smooth surface and results in a relatively greater length of life to the knife blade than in conventional constructions and requires less power for operation.

The table 30 is preferably adjusted so that it recedes downwardly from the cutting edge 18 towards its opposite edge as best indicated, with exaggeration, in Fig. 3. I find that in so tipping the table 30 the following action results,—As the knife passes through the block of stock it acts to draw the block of stock downwardly and attempts to crowd it between the cutting edge 18 and the pressure bar 31. This results in the stock being compressed along the line of severance of the strip from the block with the result that an extremely uniform thickness of strip is obtained. I further find that by increasing the angularity of the table 30 with respect to the plane of movement of the cutting edge 18 a greater compression of the wood stock occurs between the cutting edge 18 and pressure bar 31. This is extremely important because of the fact that in conventional constructions as the cutting edge 18 wears it tends to lift the stock upwardly in the hopper out of contact with the table 30, while with this construction, that is the angularly disposed table, such upward tendency is completely overcome and the proper thickness of veneer is cut from the block regardless of the condition of sharpness of the cut.

ting edge 18. These features, together with the features herein shown and completely described and claimed in my previous patent application above referred to, combine to produce a riving machine by which veneer strips of smooth finish and uniform thickness may be obtained in an efficient and extremely economical manner.

I have also discovered in connection with riving machines of this type, particularly where an angular table is provided as described to compress the wood between the cutting edge and pressure bar, that what is hereinafter referred to as the "trailing" end of the cutting edge (i. e., that end thereof which is last to engage the block) and because of the overhang of the cutting edge relative to the supporting member 13 and the lack of a further support at such end, may tend to bend upwardly when passing through the stock and thus result in the strip or plate of veneer removed from the block of stock being of greater thickness over the area severed by this end of the knife. In order to overcome this bending or distortion of this portion of the cutting edge I provide means as indicated in Fig. 1. The particular means shown comprises a lug 60 which is rigidly secured to the frame 12 and overlaps the "trailing" end of the cutting edge knife 17 adjacent said cutting edge 18. A vertical screw 61 is threaded downwardly through the lug 60 and bears against the upper face of the knife 17 adjacent the cutting edge 18 so as to maintain the adjacent portion of the cutting edge from lifting during the cutting operation. The particular means shown is, of course, merely one of a variety of different ways that this bending of the knife edge may be prevented, it being shown merely for the purpose of illustrating a suitable means for accomplishing the desired result.

It will be apparent of course that although I have shown and described the block of stock 55 as being positioned with one of its sides in parallel relationship with respect to the cutting edge 18, this may be varied in accordance with the present invention from such parallel relationship to one of a substantial angle, an important feature being such a relative position and motion of the block in relation to the cutting edge that each point of the cutting edge in passing through the block simultaneously approaches two adjacent sides of the block, the construction illustrated being for the purpose of explaining a preferable relationship, in which the line of advance is at such an angle to the grain that the effective portion of said edge has more than twice the length of the block.

It will also be apparent that the table 30 may, if desired, be permanently positioned at a definite angular relationship with respect to the plane of movement of the cutting edge 18 and the essential benefits of this

part of my invention be realized without providing for adjustment of such angularity, and furthermore, that where such adjustment of the angularity is desired, means other than the specific means shown may be employed with equally beneficial results.

Formal changes may be made in the specific embodiment of the invention described without departing from the spirit and substance of the broad invention, the scope of which is commensurate with the appended claims.

What I claim is:

1. In a riving machine, in combination, a movable knife, a substantially straight cutting edge on said knife and means for so holding a block of wood positioned to be operatively acted upon by said knife to remove strips therefrom that the grain of said wood extends at an angle of less than 45 degrees to the path of movement of said knife, and parallel to said cutting edge of said knife at all points in said path of movement.

2. In a riving machine, in combination, a movable knife, a substantially straight cutting edge on said knife and means for so holding a rectangular block of wood positioned to be operatively acted upon by said knife to remove strips therefrom that said block of wood has one of its sides at an angle of less than 45 degrees to the path of movement of said knife, and parallel to said cutting edge of said knife at all points in said path of movement.

3. In a riving machine, in combination, a knife movable in a rectilinear path, said knife having a substantially straight cutting edge, and means for holding a block of wood stock positioned with the grain of the wood at an angle of less than 45 degrees to the path of movement of said knife and parallel to said cutting edge, said means permitting a gravity feeding of said block of stock into a position to be operated upon by said knife.

4. In a riving machine, in combination, a knife having a rectilinear cutting edge and means for holding a block of wood stock movable relative to each other, said means being adapted to hold said block of stock positioned with one side thereof at an angle to the path of said movement and parallel to said cutting edge throughout said movement, and means permitting a gravity feed of said stock into operative relationship with respect to said knife.

5. In a riving machine, in combination, a knife having a rectilinear cutting edge and means for holding a block of wood stock movable relative to each other, said means being adapted to hold said block of stock positioned with one side thereof at an angle to the path of said movement and parallel to said cutting edge throughout said movement, the grain of said wood extending in approximately parallel relationship with respect to

said side, and said means permitting a gravity feed of said stock into operative relationship with respect to said knife.

6. In a riving machine, in combination, a movable knife, and means for holding a block of wood positioned to be operated upon by said knife so that the grain of said wood and the cutting edge of said knife are positioned at the same angle to the path of movement 10 of said knife and so that the effective portion of the knife edge has more than twice the length of said block.

7. In a riving machine, in combination, a movable knife, and means for holding a rectangular block of wood positioned to be operated upon by said knife, said knife being positioned with its cutting edge at an angle to the path of movement of said knife, and said block of wood being positioned with a 20 side thereof in parallel relation with respect to said cutting edge and so that the effective portion of the edge of said knife has more than twice the length of said block.

8. In a riving machine, in combination, a reciprocable knife having a cutting edge, means for holding a body of stock, the body of said knife being angularly positioned relative to the plane of movement of said cutting edge, bearing members carried by said knife 25 in spaced relation with respect to said cutting edge and between the body of said knife and said body of stock, and adjustable means for controlling the relation between said bearing members and said plane of movement of said cutting edge, whereby said body of stock is borne in spaced relation to the body of said knife.

9. In a riving machine, in combination, a reciprocable knife having a cutting edge, 40 means for holding a body of stock, the body of said knife being angularly positioned relative to the plane of movement of said cutting edge and between the body of said knife and said body of stock, and bearing members 45 threadably engaging said knife in spaced relation to said cutting edge and being adjustable with respect to said plane of movement of said cutting edge, whereby said body of stock is borne in spaced relation to the body 50 of said knife.

10. In a riving machine, in combination, a reciprocable frame having a knife supporting portion, a knife carried by said portion and having a cutting edge overhanging said portion, means securing said knife to said portion, said cutting edge being disposed angularly with respect to the path of movement of said frame, and additional means for maintaining the trailing end of said cutting edge 55 against displacement during operation of said machine.

11. In a riving machine, in combination, a reciprocable frame, a knife carried thereby having its cutting edge disposed at an angle 60 to the path of movement of said frame, means

securing said knife to said frame, and additional means co-operating between said frame and the trailing end of said knife said additional means being adjustable for maintaining the trailing end of said cutting edge 70 against upward displacement.

12. In a riving machine, in combination, a reciprocable frame, a knife carried by said frame and reciprocable therewith, said knife being provided with an overhanging cutting 75 edge disposed at an angle to the path of travel thereof, a lug carried by said frame in overlapping relationship with respect to the trailing edge of said knife, and a screw extending through said lug and bearing against 80 said knife adjacent the trailing end of said cutting edge.

13. A riving machine having, in combination, a movable knife having a cutting edge, and a co-operating table movable therewith, 85 said table having a groove therein, a guide member in said groove, said guide member co-operating with said cutting edge, shim members in said groove holding said guide member in adjustably spaced relation to said cutting edge, and a set screw retaining said guide member in said groove. 90

14. A riving machine having, in combination, a reciprocable frame, a knife supported on said frame, a cutting edge on said knife, a table co-operable with said cutting edge, pivotally mounted on said frame, and micrometer adjustment means for controlling the pivotal position of said table comprising 95 a micrometer screw threaded in said frame, a swivel connection between one end of said screw and said table, a graduated dial on the other end of said screw and a graduated pointer co-operatingly mounted adjacent said dial, on said frame. 100

15. A riving machine having, in combination, a reciprocable frame, a knife supported on said frame, a cutting edge on said knife, a table co-operable with said cutting edge, pivotally mounted on said frame, said frame having a threaded hole therein, a screw threaded in said hole, a ball on one end of said screw, said table having a socket, and a member secured to said table retaining said ball in said socket. 110

16. A riving machine having, in combination, a reciprocable frame, a knife supported on said frame, a cutting edge on said knife, a table co-operable with said cutting edge, pivotally mounted on said frame, said frame having a threaded hole therein, a screw threaded in said hole, said table and said screw having a universal connection, the lever arm between the edge of said table co-operating with said knife and said pivot being relatively shorter than the lever arm between said pivot and said universal connection, whereby accurate adjustment is made. 125

17. In a riving machine, in combination, a cutter head provided with a knife, means 130

- for directing stock into position to be operated upon by said knife, the cutting edge of said knife being positioned angularly upward, and in advance of the body thereof in respect to the direction of feed of said stock, and means having a limited surface area movable with said knife for preventing the body of said stock from contacting with the body of said knife, said means comprising a plurality of spaced bearing button members adjustably threaded into the body of said knife, and means locking said buttons in adjusted position.
18. In a riving machine, in combination, a cutter head provided with a knife, means for directing stock into position to be operated upon by said knife, the cutting edge of said knife being positioned angularly upward and in advance of the body thereof in respect to the direction of feed of said stock, and adjustable bearing means having a limited surface area both transversely and longitudinally of said cutting edge movable with said knife for preventing the body of said stock from contacting with the body of said knife, and adjustable toward or from the body of said knife in respect to the direction of feed of said stock.
19. In a riving machine; a hopper; means therebelow for supporting a block of wood for engagement by a knife edge at a predetermined distance from a lower face of said block; a knife provided with an edge whose length substantially exceeds the length of said block in the direction of the grain of said block; and means for so guiding a sliding movement of relative advance between said knife and said block as to produce a whittling type of cutting action in which the effective portion of said edge has more than twice the length of said block.
20. In a riving machine; a hopper; means therebelow for supporting a block of wood for engagement by a knife edge at a predetermined distance from a lower face of said block; a knife provided with an edge whose length substantially exceeds the length of said block in the direction of the grain of said block; and means for so guiding a sliding movement of relative advance between said knife and said block as to produce a whittling type of cutting action in which the effective portion of said edge has more than twice the length of said block, — said block-supporting means being provided with means for adjustably predetermining an inclination thereof.
21. In a riving machine; a hopper; means therebelow for supporting a block of wood for engagement by a knife edge at a predetermined distance from a lower face of said block; a knife provided with an edge whose length substantially exceeds the length of said block in the direction of the grain of said block; and means for so guiding a sliding movement of relative advance between
- said knife and said block as to produce a whittling type of cutting action in which the effective portion of said edge has more than twice the length of said block, — said block-supporting means being provided with a pressure bar and with means for adjustably predetermining a local compressive action between said edge and said bar.
22. In a riving machine; a hopper; means therebelow for supporting a block of wood for engagement by a knife edge at a predetermined distance from a lower face of said block; a knife provided with an edge whose length substantially exceeds the length of said block in the direction of the grain of said block; and means for so guiding a sliding movement of relative advance between said knife and said block as to produce a whittling type of cutting action in which the effective portion of said edge has more than twice the length of said block, — said blade being provided with means for varying the inclination thereof and with spaced block-engaging buttons, and said buttons being provided with means for predetermining the elevation thereof.
23. In a riving machine; a hopper; means therebelow for supporting a block of wood for engagement by a knife edge at a predetermined distance from a lower face of said block; a knife provided with an edge whose length substantially exceeds the length of said block in the direction of the grain of said block; and means for so guiding a sliding movement of relative advance between said knife and said block as to produce a whittling type of cutting action in which the effective portion of said edge has more than twice the length of said block, — said blade being provided with means obviating a distortion of the trailing end of said edge.
